 company

Application November 26, 1943, Serial No. 511,849
 In Great Britain November 28, 1942

8 Claims. (Cl. 9—8)

1

This invention relates to long flexible floats for use in the manufacture of water-buoyant electric cable or for other purposes. In such cable the long flexible float generally forms a core about which are disposed one or more layers of wires constituting the cable conductor, which is usually provided with a flexible waterproof covering. For some purposes it is essential that the cable should possess a high resistance to compression in a lateral direction and yet be flexible lengthwise to permit a frequent reeling and unreeling without damage. These requirements necessitate a float that is rigid in a lateral direction but locally compressible in a longitudinal direction. By the present invention we provide a float meeting these requirements. It comprises a series of laterally rigid cellular elements with gaps between successive elements, each closed by a flexible band of waterproof material which overlaps the adjacent ends of the elements and makes water-tight joints therewith.

The invention will be more fully described with the aid of the accompanying drawing wherein—

Figures 1, 2 and 3 are elevations of parts of examples of long flexible floats constructed in accordance with the invention, and

Figure 4 is an elevation of the stepped end of a buoyant electric cable embodying a float constructed according to the invention.

The examples of float shown in Figures 1 and 2 of the drawing each comprise a series of laterally rigid cellular elements 1 with gaps between successive elements. These cellular elements themselves may be of any material or materials that will result in their having adequate resistance to compression in a lateral direction. They may be closed, hollow containers which may be of metal, plywood or a tough plastic. One or both of the end walls 5 and 6 of each container may be of the same material as the circumferential wall 7 or of different material, and may or may not be flexible. Alternatively, the elements 1 may be of cellular material, for instance, cork or hard expanded rubber. The gaps between successive elements 1 are closed each by a flexible band of waterproof material which overlaps the ends of the elements and makes water-tight joints therewith. In the example of float shown in Figure 1, the gap between the first and second and second and third elements from the left are each closed by a separate band 8 applied as a convolute wrapping of tape of which the overlapping ends 9 and 10 make a tight joint with one another. The width of the tape is of the same order as the length of the elements, so that its edges overlap the adja-

2

cent ends of the circumferential walls of the elements by a substantial amount. The gaps between the third and fourth and fourth and fifth elements from the left are closed by endless bands 11, each of which is stretched elastically and slipped into position. The normal circumferential length of the endless band may be less than that of the cellular elements, so that it is under tension when in position and tightly grips the ends of the elements. In the example of float shown in Figure 2, the gaps between successive elements 1 are closed by a continuous helical wrapping 12 of tape of a width approximating to the length of an element, applied with substantial overlap, for instance, an overlap of one third of the width of the tape. The overlapping margins of the tape make joint with one another and the wrapping makes joint with the circumferential surfaces of the underlying elements.

The preferred material for the flexible bands 20 is soft vulcanised rubber, but other materials that are similar as regards their relevant physical properties may be used as substitutes for rubber. Examples are neoprene (chloroprene), alkali polysulphides, viscose. The bands may be cemented to the underlying circumferential surfaces of the elements or, if the bands are to be of vulcanised material, for instance, vulcanised rubber, they may be applied in the unvulcanised state and vulcanised to such surfaces. When bands are used that are formed by applying a continuous helical wrapping to the assembled elements, it is preferable to use unvulcanised rubber tape and later to vulcanise it to convert it into a continuous covering which is vulcanised to the elements 25 where these are of an appropriate material, for instance, hard rubber, or brass.

In the example of construction shown in Figure 3 of the drawing, the cellular elements 1 are in the form of open ended containers comprising a circumferential wall 7 and a single end wall 6. These containers are aligned with the open end of one near the closed end of the next as shown and the gaps between the circumferential walls of adjacent containers are bridged by flexible bands 8, for instance, elastically stretched endless rubber bands. The open ends of each of these containers may be strengthened by forming a circumferentially extending groove 13 therein. This also helps to retain the band in place on the container. The containers themselves may conveniently be of metal, for example, tin-plate, in which case the seam between the end wall 6 and circumferential wall 7 assists to retain 30 the band 8 on the closed end of the container.

In cases where no seam is present, there may be a groove similar to that at the open end of the container. To avoid damage to the bands the rim of each container may be bent inwardly as shown at 14.

In some cases the longitudinal tension to which the float may be subjected after its manufacture, for instance, during its incorporation in an electric cable or when in service, may render it desirable to provide some additional coupling means between successive elements in order to remove or reduce the strain on the flexible bands. In that event it is preferred, as is shown, for example, in Figure 2, to couple the containers or other cellular elements to one another along the axis of the float by flexible coupling members 15 which tend to hold them in spaced relationship and to maintain them in alignment with one another but permit the central parts of the containers to approach one another and take up positions with their axes inclined to one another. Coupling members of this form are described in the specification of my co-pending application Serial No. 511,848.

The spaces between the ends of successive closed hollow containers or elements of cellular material enclosed by the flexible bands form intervening buoyancy elements. Thus the bare improved float will be considerably more buoyant than a float consisting simply of a series of such spaced elements coupled together along the axis of the float. Where the improved float is housed within a continuous waterproof covering 16, it will, of course, present no increased buoyancy as compared with a float of similar construction not fitted with flexible bands whilst the waterproof covering 16 remains sound. Should this become damaged, however, the latter form of float will become partially flooded and its buoyancy considerably reduced but the buoyancy of the improved form of float will not be affected by damage to the sheath 16 unless it is accompanied by damage to an element in the form of a closed hollow container or to a flexible band between two elements and then only to the extent of one element.

As the volume of the enclosed spaces between the ends of successive cellular elements 7 may be reduced by a radially inward bending of the unsupported part of the band 8 or 12 due to tension in the band or pressure exerted by the medium in which the float operates, the enclosed spaces may be filled with gas under a super-atmospheric pressure sufficient wholly or in part to counteract these tendencies. This may be effected by including in each enclosed space an appropriate quantity of a substance which will liberate gas when subjected to heat. Where this course is taken it is preferable to apply the bands to the element in an unvulcanised or partially vulcanised state and to cure them by heat treating them within a mould which maintains the margins of the band in contact with the elements and serves to support the central part against the pressure of the gas generated during the heat treatment. This mould may be a temporary mould or, in the case of a float for use as a core of a buoyant cable, it may be constituted by the cable conductor stranded around it.

Where the float is to form the core of an electric cable it may be an advantage to use as the cellular elements containers made entirely of metal, for instance, of tin-plate or sheet brass and to connect them together electrically, for instance, by the use of central flexible coupling

members of metal. In the example of cable shown in Figure 4, the core is built up of a series of closed metal canisters 1 connected end to end by central flexible coupling members 15 of metal strip to form an electrically continuous core. The spaces between successive containers are closed by rubber bands 8 and the enclosure filled with gas under superatmospheric pressure. The containers themselves are also filled with gas under a similar pressure or a higher pressure. Over the core the stranded conductor is applied in two layers 17 and 19 which are of opposite lay and separated by a layer 18 of rubber-proofed fabric tape. A further layer 20 of similar tape is applied over the outer layer of wires and the whole enclosed in a sheath 16 of tough rubber or other flexible waterproof material. In such a construction the float forms a continuous electrical conductor which may be connected in parallel with the main conductor which it supports, thus increasing the conductivity of a cable of a given overall diameter, or alternatively, permitting a reduction in size of the main conductor and hence in the weight and overall size of a cable of given conductivity.

What I claim as my invention is:

1. A long flexible float comprising a series of laterally rigid cellular elements disposed with gaps between successive elements of said series and means enclosing each gap, said means comprising a flexible band of waterproof material overlapping the adjacent ends of the elements defining the gap and making water-tight joints therewith.

2. A long flexible float comprising a series of laterally rigid cellular elements with gaps between successive elements of said series and means enclosing the gaps, said means comprising for each gap, a separate flexible band which overlaps the adjacent ends of the elements defining the gap and makes water-tight joints therewith.

3. A long flexible float comprising a series of laterally rigid cellular elements with gaps between successive elements of said series and means enclosing the gaps, said means comprising for each gap, a separate flexible band in the form of a convolute wrapping which overlaps the adjacent ends of the elements defining the gap and makes water-tight joints therewith and of which the overlapping ends are joined together.

4. A long flexible float comprising a series of laterally rigid cellular elements with gaps between successive elements of said series and means enclosing the gaps, said means comprising for each gap an elastically stretchable endless band which overlaps the adjacent ends of the elements defining the gap and makes water-tight joints therewith.

5. A long flexible float comprising a series of laterally rigid cellular elements with gaps between successive elements of said series and means enclosing said gaps comprising a continuous helical wrapping of a band of flexible waterproof material, applied to said elements and making joint with the circumferential surfaces thereof, one margin of the band continuously overlapping the other and making joint therewith.

6. A long flexible float comprising a series of laterally rigid cellular elements with gaps between successive elements of the series and a continuous flexible covering vulcanised to the circumferential surfaces of the elements.

7. A long flexible float comprising a series of mutually spaced open-ended containers disposed

with the open end of one container adjacent the closed end of the next and means enclosing each gap between successive elements, said means comprising a flexible band of waterproof material overlapping the adjacent ends of the elements defining the gap and making water-tight joints therewith.

8. A long flexible float comprising a series of laterally rigid cellular elements separated by intervening buoyancy elements containing gas under super-atmospheric pressure, each of said intervening buoyancy elements being constituted by the contiguous end walls of two successive laterally rigid cellular elements and a circumferential wall formed by a flexible band of waterproof material which overlaps the adjacent ends of the two laterally rigid elements and makes joint therewith.
